UNITED STATES PATENT OFFICE.

FRANK F. BALUSEK, OF NEEDVILLE, TEXAS.

COTTON GIN.

Application filed December 14, 1925. Serial No. 75,427.

This invention relates to new and useful improvements in a cotton gin.

One object of the invention is to produce an attachment for a gin whereby the trash and motes may be more effectively separated from the lint.

Another object of the invention is to provide an attachment of the character described which is so disposed relative to the gin saws, that it will not interfere with the passage of the motes and dirt to the conveyor for them, but will deflect the lint, which has a tendency to pass, by centrifugal force, with said motes into the mote conveyor and direct the same into the lint flue through which it passes into the lint conveyor.

A further feature of the invention resides in the provision of an attachment of the character described which is of very simple construction and may be cheaply and easily produced and readily applied to any conventional type of gin, either of the brush type or of the pneumatic type.

With the above and other objects in view this invention has particular relation to certain novel features of construction, operation and arrangement of parts, an example of which is given in this specification and illustrated in the accompanying drawings, wherein:—

Figure 1 shows a fragmentary rear view of the gin, showing the breast partly broken away to disclose the attachment in its relation to the saws, and

Figure 2 shows a vertical cross sectional view thereof.

Referring now more particularly to the drawings, wherein like numerals of reference designate similar parts in each of the figures the numeral 1 designates the gin stand, as a whole, mounted on which is the enclosing body, or casing 2. Rotatably mounted in the casing there is a saw shaft 3 fixed on which are the saws 4, spaced the required distance apart. The seed cotton is fed to the saws through the hopper 5, from an overhead conveyor (not shown). These rapidly rotating saws in cooperation with

the intervening ribs 6 strip the lint from the seed and the seed passed down through the chute 7. The lint is carried on around by the saws' teeth and is freed from said saws by an air blast delivered against said saws at their rear, through the long air blast nozzle 8 in which the air duct 9 terminates.

This duct communicates with the air chamber 10 arranged behind the gin. The nozzle 8 is downwardly turned in the direction of the rotation of the saws and the air blast 60 frees the lint from the saws and carries it through the lint duct 11 to the main lint flue 12 and it passes thence to the condenser.

The motes, dirt and trash, being heavier than the lint are separated from the lint 65 by centrifugal force at the moting point 13, near the top of the saws, and over the nozzle 8 and into the mote conveyor 14.

The parts hereinabove described are common to the pneumatic type of cotton gin, 70 and now in common use. This type of gin, however, is defective in that a certain part of the lint passes by centrifugal force along with the motes into the mote conveyor and is wasted. The attachment presently to be 75 described has been designed to catch this lint, which would otherwise pass with the motes, and divert it back into the lint duct 11. To accomplish this purpose there is provided a deflector plate 15 which is disposed 80 in the rear of and spaced from the saws. This plate extends from end to end of the gin breast and at its upper edge is swung from a rod whose ends 16, 16, work through aligned bearings in the ends of the gin breast 85 and are retained in place by the nuts 17, 17. The lower edge of this deflector plate overlaps and hangs in the rear of the nozzle end of the duct 9. The lint, which has a 90 tendency to pass, by centrifugal force, with the motes, being somewhat lighter than said motes, will lag behind them and the deflector plate is positioned so as to catch this lagging lint but to permit the motes, dirt and trash to pass over into the conveyor 14. 95 The inner side of the deflector board has a lengthwise declining shield 18 on its inner side which fits over the nozzle end of the air duct 8 and prevents the congestion of the deflected lint thereon.

What I claim is:

1. In a cotton gin the combination with the saw, the air duct and the lint duct thereof, of a deflector disposed on substantially a vertical plane and spaced behind said saws and arranged above the nozzle end of said air duct, said deflector being pivoted to swing about a transverse axis with its lower end free.

2. In a cotton gin the combination with the saws, the air duct and the lint duct thereof, of a deflector spaced behind said

saws and arranged above the nozzle end of said air duct, said deflector hanging in substantially a vertical plane and extending from end to end of the gin breast with its 5 lower edge free and overlapping the nozzle end of said air duct in the rear.

3. In a cotton gin the combination with the saws, the air duct and the lint duct thereof, of a deflector swung in substantially 10 a vertical plane and spaced behind said saws and arranged above the nozzle end of said air duct and a lengthwise shield on the inner side of said deflector and fitting over the adjacent end of said air duct, the lower edge 15 of the deflector being free and being held by gravity against the rear side of said nozzle.

4. In a cotton gin the combination with the saws and the blast air nozzle thereof, 20 of a deflector depending in substantially a vertical plane and spaced behind the saws and above said nozzle and extending from end to end of the gin breast and having its ends pivotally anchored to the ends of said 25 breast, with its lower edge free and resting by gravity against the rear of said nozzle.

5. In a cotton gin the combination with the saws and the blast air nozzle thereof, of a deflector disposed in substantially a 30 vertical plane and spaced behind the saws and

above said nozzle and extending from end to end of the gin breast and having its ends anchored to the ends of said breast, so that the deflector will swing about a horizontal axis, said deflector having its lower end 35 free, a declining shield carried by said deflector and disposed over said nozzle.

6. In a cotton gin the combination with the saws and the blast air nozzle thereof, of a deflector swung in substantially a vertical 40 plane and spaced behind the saws and above said nozzle and extending from end to end of the gin breast and having its ends pivotally anchored to the ends of said breast so that the deflector will swing about a 45 horizontal axis with its lower edge free and resting against the rear of the nozzle a lengthwise shield on the side of said deflector facing the saws and disposed over said nozzle.

7. An attachment for cotton gins comprising a substantially rectangular deflector plate, a lengthwise shield carried by one side of said plate, and outwardly extending end studs carried by said plate above the 55 central horizontal line of the plate.

In testimony whereof I have signed my name to this specification.

FRANK F. EALUSEK.
